US00D785614S

(12) **United States Design Patent** (10) **Patent No.:** **US D785,614 S**
(45) **Date of Patent:** **** May 2, 2017**

(54) **SHIELD FOR A MOBILE DEVICE CASE**

(71) Applicant: **Hit Technologies Inc.**, Vancouver, Bristish Columbia (CA)

(72) Inventor: **Brooks Bergreen**, Vancouver (CA)

(73) Assignee: **Hit Technologies Inc.**, Vancouver (CA)

(**) Term: **15 Years**

(21) Appl. No.: **29/528,839**

(22) Filed: **Jun. 1, 2015**

(51) LOC (10) Cl. **14-03**

(52) U.S. Cl.

USPC **D14/250**

(57) **CLAIM**

The ornamental design for a shield for a mobile device case, as shown and described.

DESCRIPTION

FIG. 1 is a top perspective view of one embodiment of a shield for a mobile device case showing the new design; FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; FIG. 8 is a top perspective view thereof in a molded configuration;

FIG. 9 is an in-use top perspective view thereof;

FIG. 10 is a top perspective view of a second embodiment of a shield for a mobile device case showing the new design; FIG. 11 is a top view thereof;

FIG. 12 is a bottom view thereof;

FIG. 13 is a front view thereof;

FIG. 14 is a rear view thereof;

FIG. 15 is a right side view thereof;

FIG. 16 is a left side view thereof;

FIG. 17 is a top perspective view thereof in a molded configuration; and, FIG. 18 is an in-use top perspective view thereof.

The broken lines showing the remainder of the shield for a mobile device case are directed to environment. None of the broken lines form a part of the claimed design.

1 Claim, 10 Drawing Sheets
